UNITED STATES PATENT OFFICE.

ERNEST RAPATTONI, OF LOS ANGELES, CALIFORNIA.

DESIGN FOR AN AUTOMOBILE-BODY.

57,723.

Specification for Design. Patented Apr. 26, 1921.

Application filed August 23, 1920. Serial No. 405,558. Term of patent 7 years.

To all whom it may concern:

Be it known that I, ERNEST RAPATTONI, a citizen of the United States, residing at Los Angeles, in the county of Los Angeles, State of California, have invented a new, original, and ornamental Design for an Automobile-Body, of which the following is a specification, reference being had to the accompanying drawing, forming part thereof.

Figure 1 is a perspective view of an automobile body showing my new design.

Fig. 2 is a face view thereof.

I claim:

The ornamental design for an automobile body, as shown.

ERNEST RAPATTONI.
